UNITED STATES PATENT OFFICE

HARRISON R. WILLIAMS, OF NEW YORK, N. Y.

PAPER-MARKING MACHINE

Application filed March 14, 1929, Serial No. 347,001. Renewed July 19, 1932.

The present invention relates to a device for impressing upon a web of paper as it passes through a paper making machine, designs or marks which may serve to identify 5 the paper or which may serve to give the paper a distinctive character. The device may be applied to and be used in connection with a paper making machine such as a Fourdrinier machine and may be disposed at 10 any desired point in the machine after the pulp has left the screen or forming wire and has reached a stage at which it has taken on the form of a continuous web of paper.

In general the paper marking device 15 which constitutes the subject matter of the present invention may be positioned to operate on a moving paper web or sheet after it has been fully formed and after it has passed between the couch rolls. It may, however, be placed at any point after the web 20 has been formed and prior to the time it has been completely dried; the main prerequisite being merely that the web must still be in a more or less damp condition.

More specifically, the marking device may 25 preferably be placed at a point between the first and last drier rolls. At this point the web is still in a somewhat plastic condition and the subsequent action of the drier and 30 calenders is not such as to obliterate the mark.

The device comprises a flexible endless marking belt which passes preferably between two metallic rolls one of which may 35 be a drier roll, the belt passing over the upper roll and another supporting roll which is spaced therefrom.

The marking belt has substantially the 40 same width as the width of the web being formed and is provided with a vulcanized hard rubber marking surface which has a substantial amount of resiliency and yieldability. This rubber surface may be divided into a plurality of sectional areas, each area 45 being formed with the mark or design which is to be impressed upon the web so that when the web is cut into sheets each sheet will bear one or more of the impressed marks.

The rubber layer which constitutes the 50 marking face of the belt is vulcanized on a

flexible endless belt of any suitable material such as canvas or the like.

The rolls between which the marking belt travels are preferably provided with means for adjusting the pressure between the rolls 55 and for adjusting the pressure exerted upon the marking belt.

The invention will best be understood by reference to the accompanying drawings which illustrate the present preferred embodiment of the invention and the manner in which it is utilized in the association with a paper making machine, it being understood, however, that this embodiment is merely illustrative and that it is not to serve 65 as a limitation upon the invention as defined in the appended claims.

In the drawings:

Fig. 1 shows a portion of a paper making machine and the paper marking device associated therewith.

Fig. 2 is a top plan view of the paper marking device.

Fig. 3 is a developed view of the marking surface of the marking belt, and

Fig. 4 is a cross section of the belt.

Referring to the drawings, 10 indicates a part of a paper making machine and comprises the supporting frame 11, the calender 12, the conveyor belt 13, which travels around 80 the supporting rolls 14, 15 and 16 and thereby presses the paper web 17 against the calender 12. The paper marking device comprises a lower roll 18, an upper roll 19, and a marking belt 20 which travels over the upper 85 press roll 19 and the supporting roll 21. The lower press roll 18 is carried by the bearings 22 in the frame 10.

In order to provide for the variation of pressure between the rolls 18 and 19, the 90 bearings 23 of the upper roll 19 are each mounted to slide vertically between two sides of the forked supporting standards 24, one of which is mounted at each end of the roll in the manner shown. The standard 24 which is in the form of an inverted U is provided in its horizontal portion with a horizontal passage 26 thereby breaking the horizontal portion of the standard into two spaced horizontally disposed parts, the space therebe- 95 100

tween receiving a worm wheel 27. The two horizontal portions 28 and 29 of each of the supporting standards are provided with registering passages to receive an externally threaded stud 25 which is integral with the bearing block 23.

The worm wheel 27 is provided with an internal thread which cooperates with the threaded stud 25 so that when the worm wheel 10 is rotated the bearing blocks 23 are moved vertically.

In order to provide for the simultaneous and synchronous movement of the two bearing blocks 23 a horizontal shaft 30 having at 15 each end a worm gear 31, disposed to cooperate with the worm wheel 27 is provided, the shaft 31 being supported at each end by a sleeve bearing 32 which is carried by the standard 24. One end of the shaft 30 is provided with a manual operating wheel 33. It 20 will be seen therefore that by the rotation of the wheel 33 in one direction both bearing blocks 23 will be moved upwardly thereby reducing the pressure between the pressure rolls 25 18 and 19, whereas the rotation of the operating wheel in the opposite direction will move the bearing blocks 23 downwardly and thereby increase the pressure between the rolls 18 and 19.

30 The endless marking belt preferably consists of a three ply backing 34 of textile material such as canvas or the like and a marking surface of rubber 35 vulcanized onto the canvas backing. The marking surface 35 is 35 furnished with the designs or marks thereon either by engraving, or by forming the same thereon during the process of vulcanization and the rubber is made sufficiently hard so that it will impress its design upon the web 40 of paper 17 while it is still in a damp condition or while it is still in a plastic condition, the rubber, however, being also sufficiently resilient and yielding so that the web of paper will not be injured in any manner.

45 The endless marking belt is preferably of the same width as the web 17 and in the form shown in Fig. 3 is divided into a plurality of sectional areas 36, each of which is formed to contain the mark or design which is to be 50 impressed upon the web so that when the web passes through the paper making machine the mark or design will be impressed thereon at a large number of points. When the web is cut into sheets of predetermined 55 sizes each sheet will contain the mark.

While the preferred embodiment of the marking belt shown herein consists merely of a layer of flexible material such as textile material or other materials that are commonly used in belts and a marking surface of yielding hard rubber vulcanized onto the layer of backing material, if desired the back surface of the textile material namely the surface that comes in immediate contact with the pressure roll may be provided with a

very thin layer of rubber such as is obtained by impregnating that surface with rubber; this very thin layer of rubber being utilized only for the purpose of increasing the traction between the belt and the metal roll. 70

If desired one or both of the pressure rolls may be driven positively at the speed which corresponds to the speed of travel of the web through the paper making machine. The driving power is derived from the driving mechanism that is applied to the other driven elements of the paper making machine. 75

If desired the rubber layer 35 may be made in the form of a separate belt. With this 80 form of construction the rubber marking belt may be renewed from time to time, while the supporting belt 34, which serves to relieve the rubber belt of strain, may remain in use. If desired a layer of soft rubber may be disposed between the belts 34 and 35 as a cushioning layer. 85

It will be seen from the above description and from the drawings which constitute a part of the present application that I 90 have provided a paper marking device which is simple in construction and operation and which may be readily adjusted so as to provide the desired pressure depending upon the nature and condition of the paper at the time the mark is impressed thereon. The specific embodiment of the invention submitted herewith is merely illustrative and it is apparent that many changes may be made by persons skilled in the art without departing from the spirit of my invention as 95 defined by the appended claims. 100

What I claim is:

1. In combination with a paper making machine through which the paper passes as a continuous web, a pair of metal rolls, the paper web being arranged to pass continuously between said rolls, a vertically slideable bearing block disposed at each end of one of said rolls, a guide for each of said bearing blocks, a vertically disposed threaded stud integral with each of said bearing blocks, an internally threaded worm wheel carried by each of said studs, means for holding said worm wheels against vertical movement, and means for rotating said worm wheels synchronously. 110

2. In combination with a paper making machine through which the paper passes as a continuous web, a pair of metal rolls, the paper web being arranged to pass continuously between said rolls, a vertically slideable bearing block disposed at each end of one of said rolls, a guide frame for each of said bearing blocks comprising a pair of spaced vertical legs, and a pair of spaced transverse members, a threaded stud integral with each of said blocks, an internally threaded worm wheel carried by each of said studs, worm wheels being disposed between said spaced 120 125 130

transverse members and manually operable means for rotating said worm wheels synchronously.

3. In a machine for impressing a mark on a continuous web of paper in the process of manufacture after the web has been subjected to drying and before drying is completed; an endless marking belt comprising a textile material and a layer of rubber coextensive with said material and vulcanized thereon, said rubber being formed to provide a mark to be impressed in the paper, said rubber having sufficient hardness and yieldability to impress a clear mark without injury to the web.

In testimony whereof I have affixed my signature to this specification.

HARRISON R. WILLIAMS.
